J. GORDON

PIPE HANGER

Filed Dec. 20, 1922

UNITED STATES PATENT OFFICE.

JOHN GORDON, OF MINNEAPOLIS, MINNESOTA.

PIPE HANGER.

Application filed December 20, 1922. Serial No. 607,936.

To all whom it may concern:

Be it known that I, JOHN GORDON, subject of the King of Great Britain, residing at Minneapolis, in the county of Hennepin and State of Minnesota, have invented certain new and useful Improvements in Pipe Hangers, of which the following is a specification.

This invention relates to an improved pipe hanger particularly adapted for supporting stove pipes or the like, and seeks, as one of its principal objects, to provide a device of this character which will be simple and efficient in construction and which will be adapted for a wide range of use.

The invention has as a further object to provide a pipe hanger which may be adjusted in length.

And the invention has as a still further object to provide a hanger embodying a pipe encircling strap which may be readily adjusted to meet the requirements of pipes of different diameters.

Other and incidental objects will appear hereinafter.

In the drawings:

Figure 1 is an elevation showing one of my improved hangers in connection with the flue pipe of a conventional gas range,

Figure 2 is an enlarged sectional view of the device,

Figure 3 is a transverse sectional view on the line 3—3 of Figure 2, looking in the direction of the arrows, and

Figure 4 is a fragmentary sectional view showing a slight modification of the invention.

In carrying the invention into effect, I form my improved device with a lineally adjustable stem which is composed of a plurality of complementary sections including a barrel 10 into one end of which is threaded a supporting rod 11 having a circular base flange 12 and extending from the adjacent end of the rod axially thereof is a wood screw 13 suitably secured to the rod. Threaded into the barrel at its opposite end is an outer rod 14 provided at its outer end with a circular head 15 and mounted upon the rod is a pipe strap 16. This strap may be formed from a piece of suitable sheet metal and is provided at one end with a head 17 overlying the head 15 of the rod 14 and extending through the head 17 is a screw or other suitable fastening device 18 threaded

into the rod detachably connecting the strap therewith. Near its outer end the head is provided with a transverse slot 19 adapted to receive the free end of the strap therethrough. It is now to be observed that the rod 11 is provided with a left hand thread while the rod 14 is provided with a right hand thread, the barrel being, of course, threaded accordingly so that by rotating the barrel the hanger may be readily adjusted

into the rod detachably connecting the strap therewith. Near its outer end the head is provided with a transverse slot 19 adapted to receive the free end of the strap therethrough. It is now to be observed that the rod 11 is provided with a left hand thread while the rod 14 is provided with a right hand thread, the barrel being, of course, threaded accordingly so that by rotating the barrel the hanger may be readily adjusted

into the rod detachably connecting the strap therewith. Near its outer end the head is provided with a transverse slot 19 adapted to receive the free end of the strap therethrough. It is now to be observed that the rod 11 is provided with a left hand thread while the rod 14 is provided with a right hand thread, the barrel being, of course, threaded accordingly so that by rotating the barrel the hanger may be readily adjusted

Having thus described the invention, what is claimed as new is:

A pipe hanger comprising a barrel reversely threaded interiorly at its opposite end portions, a suspending rod engaged in one end of the barrel, a flange on said rod at the free end thereof to bear against a fixed support, a securing device projecting from said flange, a hanger rod engaged in

the opposite end of the barrel, a head on the outer end of the hanger rod, and a pipe-encircling band detachably secured across and against said head, rotation of the barrel effecting simultaneous endwise adjustment of the rods. 10

In testimony whereof I affix my signature. 15

JOHN GORDON. [L.S.]
